(57) **CLAIM**

The ornamental design for a zippered pouch for a garment, as shown and described.

DESCRIPTION

The zippered pouch could be constructed of a waterproof material such as nylon. Consequently this functional clothing item could allow items such as money, identification, keys, and other items to be easily stored and protected from perspiration or rain.

FIG. 1 is a front view of a zippered pouch for a garment showing my new design;

FIG. 2 is a rear view thereof;

FIG. 3 is a left side view thereof;

FIG. 4 is a right side view thereof;

FIG. 5 is a top view thereof; and,

FIG. 6 is a bottom view thereof.

The broken line showing of the environment in FIG. 1 is for illustrative purposes only and forms no part of the claimed design.
